UNITED STATES PATENT OFFICE.

GOGU CONSTANTINESCO, OF LONDON, ENGLAND, ASSIGNOR OF ONE-HALF TO WALTER HADDON, OF LONDON, ENGLAND.

HYDRAULIC POWER TRANSMISSION.

1,211,679.

Specification of Letters Patent.

Patented Jan. 9, 1917.

Application filed February 27, 1914. Serial No. 821,376.

To all whom it may concern:

Be it known that I, GOGU CONSTANTINESCO, a subject of the King of Roumania, and residing at 8 Lichfield road, Kew Gardens, London, England, have invented certain new and useful Improvements in and Relating to Hydraulic Power Transmission, of which the following is a specification.

The present invention relates to the transmission of energy by hydraulic means.

The invention consists in means for transmitting continuous rotary motion between two points, and reversing such motion by means of a number of columns of fluid having an alternating or sinusoidal motion.

The invention consists more specifically in means for converting in a suitable generator mechanical energy in the form of rotary motion at one place into periodic to-and-fro motion of a number of columns of fluid contained in suitable conduits, conducting said columns to a suitable receiver and re-converting the periodic to-and-fro motion into rotary motion in either direction.

The invention also consists in reversing the rotary motion in a hydraulic transmission apparatus having three or more phases, by interchanging the communications between the working columns of liquid and the several cylinders of the receiver or generator.

Referring to the accompanying drawings Figure 1 is a transverse section; Fig. 2 a sectional plan; Fig. 3 a side view; and Fig. 4 a plan, of one form of generator according to the invention. Fig. 5 is a section on the line A—A, Fig. 1. Fig. 6 is a diagrammatic view showing the generator and receiver and their connections. Fig. 7 is a cross section, and Fig. 8 a longitudinal section of a suitable reversing valve.

In the form of the invention illustrated there are provided three pipes leading from the generator to the receiver, these pipes communicating with the apertures *a*, *b*, *c*, respectively. These apertures lead into piston chambers *a'*, *b'*, *c'*, each of which is provided with three pistons *p'*, *p²*, *p³*, arranged radially as shown in Fig. 1. The pistons are operated by means of an eccentric *d*, operating through a ball bearing on the inner ends of the pistons. The eccentric is mounted on the driving shaft *e* driven by the pulley *f*. The spaces com-

municating with the apertures *a*, *b* and *c* are filled with liquid, and the pistons may be kept up against the eccentric by means of springs. The receiver may be similarly constructed. The fluid used in the pipes in the above described transmission system may be any suitable liquid medium.

It will be seen that in the arrangement shown in Figs. 1 to 5, the displacement of liquid in any one chamber will be that due to the sum of the displacement of the three pistons which work in that chamber, giving a more uniform sinusoidal motion than would be obtained if only one piston were used in each chamber.

It will be understood that the phenomena connected with the system of transmission above described are closely analogous to the phenomena connected with alternating electric currents. Consequently it is found that for transmitting power over great distances, it is desirable that high pressure and short period be employed in order that the amount of liquid in motion may be small and the size of the pipes also small, the frequency and pressure for long distance transmission being so chosen that the weight of the connecting pipes shall be a minimum. For instance, with a three-cylinder generator and motor making 3000 revolutions per minute, the frequency will be 50 pulsations per second. It is thus possible, with a very small and simple apparatus, to transmit considerable driving couple over a long distance synchronously and without great loss.

The present system of transmission has an important practical advantage over electrical transmission in that it may be employed for extremely low speeds of rotation. It is particularly applicable for transmitting power to machines in workshops from prime movers, to the propeller shafts of ships, and in general in all situations where synchronism is important.

In order to reverse a three-phase arrangement such as that above described, it is only necessary to interchange the connections of two of the pipes, the change being made when the piston in communication with the other pipe is at its dead center, and this method of reversal is applicable to reversal in systems having more than three pipes, by a suitable change of connections. Any suitable switch, such as interconnected three-

way cocks operated by a single lever movement may be provided for this purpose.

The generator 1 and receiver 2, with their connecting pipes 3, 4, 5, are diagrammatically illustrated at Fig. 6, the reversal of motion of the receiver being effected by interchanging the connections of the pipes 4 and 5 with the generator, by the change over cock 6, which may be of any suitable known 10 type.

A suitable type of valve for effecting the reversal is shown in Figs. 7 and 8. This comprises a plug 7 fitting into a block 6, and provided with two passages, one adapted to 15 connect the pipe 4 either with the pipe 4^a or the pipe 5^a, and the other adapted to connect the pipe 5 either with pipe 5^a or the pipe 4^a. This valve is diagrammatically shown in Fig. 6. When it is desired to 20 reverse the direction of motion, the valve is changed over, so as to interchange the connections of the pipes 4 and 5 with the generator, this being effected at the moment when the piston in the chamber of the 25 generator connected with the pipe 3 is at its dead center, so that there will be no resistance to the reversal of the motion by the piston in the chamber connected with the pipe 3.

It will be seen from Figs. 6, 7 and 8 that 30 when the cock 7 is in the position shown in the full lines in Fig. 7, the pipe 4 is connected to the pipe 4^a and the pipe 5 is connected to the pipe 5^a. Assume that the rotation of both generator and receiver in this case is 35 in the direction of the hands of the clock, we shall then have the pistons of the three cylinders differing in phase angle by 120 degrees. Assume now that the pistons con-

nected to the pipe 3 are at the end of their stroke, then the pistons connected to the 40 pipes 4 and 5 will be symmetrically placed as regards their position in the stroke but will be moving in opposite directions, one moving in and the other out. If then the current on these pistons be reversed by 45 changing over the switch to the dotted position (Fig. 7) the motion of the two pistons will be reversed so that the rotating field produced by the three pistons will be 50 changed in direction and reverse rotation will occur.

Having now described my invention, what I claim as new and desire to secure by Letters Patent is:—

Apparatus for hydraulic transmission of 55 energy, comprising in combination, a generator, a plurality of chambers in said generator, pistons in each of said chambers, a common eccentric actuating said pistons, a receiver, including a plurality of chambers, 60 pistons in said chambers, and a common eccentric acted on by said pistons, pipes connecting each of said chambers in said generator with one of said chambers of said receiver, and means for interchanging the connections of said pipes and said receiver or generator in such a manner as to produce reverse rotation.

In testimony whereof I have signed my name to this specification in the presence of 70 two subscribing witnesses.

GOGU CONSTANTINESCO.
